G. W. WATSON,
BOILER TUBE CLEANER,
APPLICATION FILED DEC. 16, 1915

1,225,292.

Patented May 8, 1917.

UNITED STATES PATENT OFFICE.

GLENN W. WATSON, OF DETROIT, MICHIGAN, ASSIGNOR TO DIAMOND POWER SPECIALTY COMPANY, OF DETROIT, MICHIGAN, A CORPORATION OF MICHIGAN.

BOILER-TUBE CLEANER.

1,225,292.

Specification of Letters Patent.

Patented May 8, 1917.

Application filed December 16, 1915. Serial No. 67,270.

To all whom it may concern:

Be it known that I, GLENN W. WATSON, a citizen of the United States of America, residing at Detroit, in the county of Wayne 5 and State of Michigan, have invented certain new and useful Improvements in Boiler-Tube Cleaners, of which the following is a specification, reference being had therein to the accompanying drawings.

10 The invention relates to boiler tube cleaners of that type in which a steam discharge nozzle is rotatively adjusted to sweep a predetermined space with a jet discharged therefrom. The present invention comprises 15 the novel construction of operating mechanism for rotatively adjusting the nozzle which insures a slow and steady movement thereof that will effect a thorough cleaning.

20 In the drawings:

Figure 1 is a sectional side elevation showing a portion of a tubular boiler and my improved mechanism applied thereto; and

Fig. 2 is a front elevation.

25 A is a furnace wall, B are tubes within the furnace chamber and C is a rotative cleaner tube projecting through the furnace wall and having one or more laterally-projecting discharge nozzles D registering 30 with spaces between the tubes. E is the steam supply conduit outside of the furnace wall, which is connected with the rotative tube C by a laterally-deflected fitting or 35 goose-neck F and a swivel G. H is a spur-gear mounted upon the rotative tube C, and I is a pinion in mesh with said gear, which 40 is mounted upon a pin J secured to a boss K on the fitting F. L is a sheave or sprocket-wheel also mounted on the pin J 45 and coupled to the pinion I. M is a bracket-arm secured to a bearing N in the furnace wall in which the tube C is journaled and also connected to the inner end of the pin J forming an anchoring support for the same 50 and the fitting F. O is a chain for engaging the sheave or sprocket by means of which it may be rotated from a distance.

With the construction as described, in operation, the rotation of the sheave L by the 55 chain O will be transmitted through the step-down gearing formed by the pinion R and spur-gear Q to the rotative tube C, imparting to the latter a slow and steady movement. This will insure a thorough

cleaning of all the space swept by the jets 55 from the nozzles D.

What I claim as my invention is:—

1. The combination with a furnace wall, of a rotatively adjustable cleaner tube extending through said wall and provided 60 with one or more jet nozzles, a supply conduit for said tube, a fitting for connecting said supply conduit with said tube having a swivel connection with the latter and including a laterally deflected portion or goose-neck, a spur-gear mounted on said tube, a pinion in mesh with said spur-gear having a journal bearing on the laterally deflected portion of said fitting, and manually-operable means for rotating said pinion to impart a slow and steady movement to said 65 rotative tube.

2. The combination with a furnace wall, of a rotative tube projecting through said wall and having one or more jet nozzles, a 70 supply conduit outside said wall, a fitting for connecting said supply conduit with said rotative tube having a swivel connection with the latter and including a laterally deflected portion or goose-neck, a spur-gear 75 mounted on said rotative tube, a pinion meshing with said spur-gear, a pin forming a journal for said pinion mounted in the laterally deflected portion of said fitting and projecting laterally therefrom, a sheave 80 also journaled on said pin and coupled to said pinion, and a chain for rotating said sheave and imparting through the medium of said pinion and spur-gear a slow and 85 steady rotation to said tube. 90

3. The combination with a furnace wall, of a rotative tube extending therethrough having one or more jet nozzles at its inner end, a bearing for said tube in said furnace wall, a supply conduit outside of said wall, 95 a fitting connecting said supply conduit with said rotative tube including a laterally-deflected portion or goose-neck and a swivel connection for said rotative tube, a spur-gear mounted on said rotative tube, a pinion meshing with said spur-gear, a pin 100 forming a journal bearing for said pinion mounted in a boss on said fitting, a sheave connected to said pinion and also journaled on said pin, a chain for operating said 105 sheave, and a bracket member connecting a bearing in said furnace wall with said pin and forming an anchorage for said fitting.

4. The combination with a furnace wall, of a rotatively adjustable cleaner tube extending through said wall and provided with one or more jet nozzles, a bearing for said tube in said furnace wall, a bracket arm projecting from said bearing, a gear mounted upon said tube outside of said wall, a pinion in mesh with said gear, a supply conduit having swivel connection with said tube and having a portion return-bent in

proximity to said pinion, and coacting with said bracket arm to support the pinion, and means for rotating said pinion.

In testimony whereof I affix my signature in presence of two witnesses.

GLENN W. WATSON.
